UNITED STATES PATENT OFFICE.

GEORGE H. KIRK, OF PHILADELPHIA, PENNSYLVANIA.

CANDLE.

SPECIFICATION forming part of Letters Patent No. 276,602, dated May 1, 1883.

Application filed January 31, 1883. (No model.)

To all whom it may concern:

Be it known that I, GEORGE H. KIRK, a citizen of the United States, residing at Philadelphia, in the county of Philadelphia and State of Pennsylvania, have invented a new and useful Improvement in Candles Used for Giving Light, of which the following is a specification.

My invention consists in the combination, with a candle, of an inflammable material which will kindle by friction and ignite the wick of the same.

Two methods of putting my invention in practice are illustrated in the accompanying drawings, in which—

Figure 1 is a longitudinal surface view, and Fig. 2 is a longitudinal section.

Similar letters refer to similar parts in both views.

A is a candle used for giving light, and B its wick, in combination with a combustible material which will kindle by friction and

ignite the said wick. As shown at C, Figs. 1, 2, a match, *a*, is placed within or contiguous to the wick, and at *b*, Fig. 1, the candle prepared for ignition by dipping the wick in an inflammable material.

The invention can be applied at either or both ends of a candle.

I am aware that matches or tapers consisting of fiber saturated with wax or other suitable substances, provided at the end with a compound which will ignite by friction, have long been known and used, and this I do not claim.

I claim as my invention—

As a new article of manufacture, a candle provided at the end with a combustible material which will kindle by friction and ignite the wick of said candle.

GEORGE H. KIRK.
